LIQUID DISPENSING APPARATUS

Herbert D. Schoelzel and Joseph D. Henderson,
San Antonio, Tex.

Application November 23, 1956, Serial No. 623,893

2 Claims. (Cl. 222—381)

The present invention relates to apparatus for dispensing a liquid such as hairdressing liquid, perfume, or the like.

An object of the present invention is to provide a liquid dispensing apparatus for dispensing a liquid such as hairdressing liquid, perfume, hand lotion, or other toilet liquid which lends itself to installation in public washrooms, trains, and other vehicles used by the traveling public, one which is sturdy in construction and simple in structure, one economical to manufacture and assemble, and one highly effective in operation.

These and other objects and advantages of the present invention will be fully apparent from the following description when taken in connection with the annexed drawings, in which:

Figure 1 is a sectional view of the apparatus of the present invention as seen from one side thereof;

Figure 2 is a sectional view taken on line 2—2 of Figure 1;

Figure 3 is a sectional view taken on line 3—3 of Figure 1;

Figure 4 is a sectional view taken on line 4—4 of Figure 1;

Figure 5 is a sectional view taken on line 5—5 of Figure 1; and

Figure 6 is a sectional view, on an enlarged scale, taken on line 6—6 of Figure 5.

Referring in greater detail to the drawings in which like numerals indicate like parts throughout the several views, the liquid dispensing apparatus of the present invention comprises an upright closed housing 10 having therein a receptacle 11 for holding a supply of the liquid to be dispensed.

A hollow piston rod 12 having a piston 13 on one end thereof is vertically positioned within the receptacle 11 with the piston 13 adjacent to and spaced from the bottom 14 of the receptacle 11. The piston rod 12 has a portion adjacent the upper end thereof exteriorly of and above the top of the receptacle 11.

A dispensing conduit 15 has one end connected in communication with the interior of the hollow piston rod 12 and has its other end remote from the receptacle 11 and projecting outwardly of the housing 10 beneath a shield 16 formed integrally with the front wall of the housing 10.

An upstanding support member 16' is positioned within the receptacle 11 and has the upper end thereof exteriorly of and above the top of the receptacle 11. A vertically disposed pump cylinder 17 having its lower end open is carried by the lower end of the support member 16' for movement therewith and is positioned within the receptacle 11 so that the lower end of the pump cylinder 17 faces toward and is spaced above the bottom 14 of the receptacle 11. The pump cylinder 17 is mounted upon the piston 13 for up and down movement responsive to the upward and downward movement of the support member 16.

2

A spring 18 is positioned between the upper face of the piston 13 and the upper end of the pump cylinder 17 for urging the pump cylinder 17 to its down position as shown in full lines in Figure 1.

5 Means is provided for effecting the upward and downward movement of the pump cylinder 17 and the support member 16' and comprises a horizontally disposed rocker arm 19 mounted upon the horizontally disposed long leg of a bracket 21 which is attached by its short leg to the rear wall of the housing 10. The mounting of the rocker arm 19 includes a shaft 22 fixedly secured thereto and having collars 23 and 24 on each side of the long leg of the bracket 21 for supporting the rocker arm 19 for rocking movement about the shaft 22 as a horizontal axis.

The wing nut 25 is threadedly engaged upon the upper end portion of the support member 16' and connects the upper end of the support member 16' to the rocker arm 19 so as to effect the upward movement of the support member 16' responsive to the tilting movement from the full line position to the dotted line position in Figure 1.

The shaft 22 has a downwardly extending portion 26 from which projects an extension 27.

A coin slot mechanism of conventional construction is indicated by the reference numeral 28 and includes a plunger 29 disposed horizontally and having a finger hook 31 on the end of the plunger 29 which is exteriorly of the housing 10. The other end of the plunger 29 carries an L-shaped actuating element 32 having its long leg extending horizontally and longitudinally of the plunger 29 and having its short leg 33 projecting upwardly and engageable with the lower end of the extension 27 upon execution of forward movement of the plunger 29 within the coin slot mechanism 28.

35 Latch means is provided for holding the extension 27 in the position in which it is moved by engagement with the short leg 33 of the element 32 upon execution of movement of the plunger 29 forwardly. Specifically this latch means comprises an arm 34 having one end mounted upon a bracket 35 carried by the back wall of the housing 10 for movement from the full line position to the dotted line position shown in Figure 1. The free end of the arm 34 rests upon the upper end of the short leg 33 of the element 32 and is lowered to the dotted line position by the forward movement of the plunger 29 carrying the element 32 forwardly. The extension 27 has a portion underlying the arm 34 and receivable in any one of the notches 36 in the arm 34. At the limit of its forward movement, the plunger 29 will move the extension 27 to a rearwardly swung position with respect to the housing 10 and the extension 27 will be held in that position by the one notch 36 on the arm 34 into which the extension has been releasably secured. Upon

40 movement of the plunger 29 outwardly of the housing 10, or rearwardly, the short leg 33 of the element 32 will serve to raise the arm 34, releasing the extension 27 from the one notch 36 and permitting the extension 27 to return to its original position and permitting the support member 16' to be lowered under the urging of the spring 18.

45 The coin slot mechanism 28 contains within a box 37 a conventional coin-rejecting and passing mechanism which permits the plunger 29 to be moved forwardly when the proper coin has been inserted within the plunger 29. This mechanism is not further described or illustrated as not being a part of the present invention.

50 Check valve means is provided in the lower open end of the cylinder 17 and includes a ball 38 positioned within the cylinder 17 and seatable in the open end which is positioned adjacent to and spaced above the bottom 14 of the receptacle 11. The ball 38 is movable inwardly

of the open end of the cylinder 17 in response to downward movement of the cylinder 17 to fill the cylinder with a charge of the liquid contained in the receptacle 11 and will move to close the open end of the cylinder 17 responsive to the execution of the upward movement of the cylinder 17 and the support member 16 to retain the charge of liquid within the cylinder 17 and permit the piston 13 to force the charge of liquid upwardly into the hollow piston rod 12.

Means is provided on the end of the rocker arm 19 remote from its point of connection with the support member 16 for limiting the downward movement of the support member 16 and the attached cylinder 17. Specifically this means comprises a bolt member 39 secured by lock nuts 41 and 42 to the rocker arm 19, the upper end of the bolt 39 bearing against an abutment plate 43 provided on the underside of the top of the housing 10. By adjustment of the bolt 39 relative to the rocker arm 19 the distance of travel of the support member 16 and the resultant movement of the cylinder 17 permits the amount of liquid being dispensed to be accurately and efficiently controlled.

Means is provided stopping the mechanism of the dispensing apparatus from working upon exhaustion of the supply of liquid within the receptacle 11 and comprises a float element 44 carried on the lower end of a rod 45 which is journaled in brackets 46 and 47 projecting from one side of the piston rod 12. The upper end portion of the rod 45 is bent downwardly as at 48 and is slidably supported in other brackets 49. The lower end of the downwardly bent portion 48 of the rod 45 is receivable within a hole provided in the long leg of the element 32 thereby locking the plunger 29 against movement into the housing 10 when the float element 44 is at the limit of its downward movement position. An adjusting screw 51 permits the adjustment of the float element 44 relative to the supporting rod 45.

Referring to Fig. 6, it will be seen that the receptacle 11 is provided with a cover 51 over which extends a plate member 52 having a vertically extending flange 40 bolted to the rear wall of the housing 10.

A nipple 53 surrounds the upper end of the hollow piston rod 12 and forms a means for securement of the piston rod to the plate 52 and to the conduit 15. The nipple 53 has a tapered inner surface on which rests a ball 54 forming another check valve and operable to permit liquid to flow upwardly into the conduit 15 but to prevent its flow of liquid downwardly into the piston rod 12.

In use, the receptacle 11 is easily demounted from the cover 51 for filling with the liquid to be dispensed and as easily replaced. Upon insertion of a coin into the coin slot of the plunger 29, the plunger 29 may be pushed forwardly into the housing 10 to effect the tilting movement of the rocker arm 19 and the subsequent raising of the cylinder 17 which pumps a charge of the liquid to be dispensed upwardly and out of the dispensing conduit 15 onto the hands of the user, the liquid being indicated by droplets 55 in Figure 1.

The amount of the liquid being dispensed is easily controllable by the adjustment of the bolt 32 which limits the tilting movement of the rocker arm 19.

The dispensing apparatus according to the present invention will be found to be useful for installation in public places such as washrooms on passenger carrying vehicles and in hotels and the like where it is desirable to have a dispensing apparatus for the sale of and application of liquids such as hairdressing creams, hand lotions and the like.

What is claimed is:

1. A liquid dispensing apparatus comprising a receptacle adapted to contain a body of liquid to be dispensed, a hollow piston rod having a piston on one end thereof vertically positioned within said receptacle with said piston adjacent to and spaced from the bottom of said

receptacle and having a portion adjacent the upper end thereof exteriorly of and above the top of said receptacle, a dispensing conduit having one end thereof connected in communication with the interior of said piston rod and having the other end remote from said receptacle, an upstanding support member positioned within said receptacle and having the upper end thereof exteriorly of and above the top of said receptacle and having the lower end positioned above the bottom of said receptacle and connected to said receptacle for up and down movement, a vertically disposed pump cylinder having the lower end open carried by the lower end of said support member for movement therewith and positioned so that the lower end of said cylinder faces toward and is spaced above the bottom of the receptacle and mounted on the piston for sliding up and down movement in response to movement of said support member, check valve means normally closing the open lower end of said cylinder and operable to move to the open position responsive to the execution of the down movement of said support member to fill the cylinder with a charge of said liquid and to move to the closed position responsive to the execution of the up movement of said support member to retain the charge of liquid within said cylinder, said piston upon execution of the up movement of the cylinder pumping said liquid charge into the lower end of said piston rod, a horizontally disposed rocker arm mounted in said receptacle for rocking movement about a horizontal axis and having one end connected to the upper end of said support member for effecting the up movement of the latter, means on the other end of said rocker arm for limiting the down movement of said support member, a horizontally disposed plunger having one end within and adjacent the upper end of said receptacle and having the other end exteriorly of said receptacle and connected to said receptacle for forward and backward movement, and an upright extension dependently carried by said rocker arm and having its lower end engageable by said one end of said plunger and operable upon execution of forward movement of the latter to effect the movement of said rocker arm to the position in which said support member is in the up movement position.

2. A liquid dispensing apparatus comprising a receptacle adapted to contain a body of liquid to be dispensed, a hollow piston rod having a piston on one end thereof vertically positioned within said receptacle with said piston adjacent to and spaced from the bottom of said receptacle and having a portion adjacent the upper end thereof exteriorly of and above the top of said receptacle, a dispensing conduit having one end thereof connected in communication with the interior of said piston rod and having the other end remote from said receptacle, an upstanding support member positioned within said receptacle and having the upper end thereof exteriorly of and above the top of said receptacle and having the lower end positioned above the bottom of said receptacle and connected to said receptacle for up and down movement, a vertically disposed pump cylinder having the lower end open carried by the lower end of said support member for movement therewith and positioned so that the lower end of said cylinder faces toward and is spaced above the bottom of said receptacle and mounted on said piston for sliding up and down movement in response to the movement of said support member, spring means operatively connected to said cylinder urging said cylinder to the down movement position, check valve means normally closing the lower open end of said cylinder and operable to move to the open position responsive to the execution of said down movement of said support member to fill the cylinder with a charge of said liquid and to move to the closed position responsive to the execution of the up movement of said support member to retain the charge of liquid within said cylinder, said piston upon execution of the up movement of the cylinder pumping said liquid charge into the lower end of said piston rod, a horizontally

disposed rocker arm mounted in said receptacle for rocking movement upon a horizontal axis and having one end connected to the upper end of said support member for effecting the up movement of the latter, means on the other end of said rocker arm for limiting the down movement of said support member, a horizontally disposed plunger having one end within and adjacent the upper end of said receptacle and having the other end exteriorly of said receptacle and connected to said receptacle for forward and backward movement, an upright extension dependingly carried by said rocker arm and having its lower end engageable by said one end of said plunger and operable upon execution of forward movement of the latter to effect the movement of said rocker

5 arm to the position in which said support member is in the up movement position, and latch means engaging said extension for holding the latter in the position to which it is moved upon execution of forward movement of said plunger and operable to release said extension upon execution of backward movement of said plunger.
